HAT

Marguerite Miller, Great Neck, N. Y.

Application March 20, 1937, Serial No. 132,003

4 Claims. (Cl. 2—175)

My invention relates to hats and refers particularly to hats adapted for washing and ironing.

It is frequently desirable to clean hats made of soft felt and other similar materials, but because of the somewhat annular and dome-like formation of these articles, the cleansing and pressing present such difficulties that it is usually impossible to obtain satisfactory results without the necessary machinery and forms.

10 The object of my invention is the production of hats of such formation that they can be readily opened, or spread, into such a physical condition that they can be readily and thoroughly washed and ironed.

15 It is evident that in order to accomplish these desirable results it is necessary that the hat material when in its disassembled condition have as few wavy or curved surfaces as possible to allow of satisfactory ironing with a minimum of care and trouble.

20 Attempts have been made to produce a hat having the required properties, but they have not been effective.

In the production of hats of this character it is necessary that the crown and the brim be of such formation that it can be positioned in a more, or less, flat state, and that the flatter and smoother the thus disassembled hat, the more easily it is washed and ironed.

25 It is further evident that the line of severance in the crown and brim must be of such a character that it will not affect its attractive appearance, and should be such as to improve the appearance.

The device of my invention overcomes the 30 above mentioned, and other, objectionable features of prior hats adapted for this purpose, and presents hats which can be disassembled with a minimum of waves and which will at the same time add to its attractiveness.

35 The advantages of the hats of my invention will be evident upon a consideration of my specification and accompanying drawing, in which similar parts are designated by similar numerals.

40 Figure 1 is a perspective view of one form of the hat of my invention in its normal condition.

45 Figure 2 is a top view of the hat of Figure 1 in its open position.

Figure 3 is a section through the line 3—3 of Figure 1.

50 Figure 4 is a broken perspective view of a hat of my invention, showing a modified form of brim closure.

The particular form of the device of my invention shown in the accompanying drawing comprises a hat having the soft, pliable, crown 10

made of felt or other suitable material, and the brim 11 which may be of any suitable material and may be integral with the crown 10 or attached thereto in any desired manner. The hat may be lined, carry a sweat-band, an exterior ribbon 5 band, or otherwise adapted for use.

The crown is cut, or split, spirally, 12, the severance commencing preferably at, or near, a point of the connecting line of the crown and brim, and extending spirally and upwardly 10 around the crown. The edges of the crown along the line of spiral severance carry removable connecting means, shown as a so-called "Zipper" 13 whereby the severance edges may be readily connected and disconnected.

15 The brim 11 is not a continuous closed member, but is cut, or slit, and the two end portions 14 and 15 overlap, the lower end portion 15 carrying the male members 16, 16 of a clasp, while the upper end portion 14 carrying the female members 17, 17 of the same clasp. The end members 14 and 15 are disconnected to the crown 10 at the terminal of the spiral opening 12.

20 It is evident, therefore, that if the clasp members 16, 16 and 17, 17 be disconnected and the spiral zipper 13 be opened by means of the ordinary operating member 18, the entire hat as a 25 unit may be opened into the position shown in Figure 2.

25 In the modification of my device shown in Figure 4, the brim of the hat is an ordinary brim in which a slit 19 has been made by cutting, or otherwise. To the end member 14 of the brim a closure member 20 has been stitched as at 21, or otherwise attached thereto, the underside of 30 which carries the female elements 22, 22 of a clasp, the upper surface of the end member 15 carrying the corresponding male elements.

35 It is evident that the "Zipper" closure member can be so arranged as to make as many spirals 40 around the hat crown as may be desired.

The operation of this modified form of my device is similar to that previously described.

45 It will thus be seen that my hat presents a decorative appearance, especially when the "Zipper" element is of a different color from that of the hat; that it can be readily disassembled and assembled, and that when it is in its open condition, it allows of ready and thorough cleaning and washing operations, and that because of its strip-like formation it can be readily ironed or pressed.

50 I do not limit myself to the specifically mentioned material, size or arrangement of parts as 55

these are given solely for the purpose of clearly describing my invention.

What I claim is:

- 5 1. In a hat, a crown having a spiral slit therein extending from the periphery of said crown and circumferentially around the side of said crown and toward the top thereof and separable means adapted to allow the opening and closing of said slit.
- 10 2. In a hat, a crown having a spiral slit therein extending from the periphery of said crown and circumferentially around the side of said crown and toward the top thereof and slide fastening means adapted to allow of the opening and closing of said slit.
- 15

3. In a hat, a crown having a spiral slit therein, the adjacent turns of which are approximately equi-distant from each other and extending from the periphery of said crown and circumferentially around the side of said crown and toward the top thereof and separable means adapted to allow of the opening and closing of said slit.

4. In a hat, a crown having a spiral slit therein, the adjacent turns of which are approximately equi-distant from each other and extending from the periphery of said crown and circumferentially around the side of said crown and toward the top thereof and slide fastening means adapted to allow of the opening and closing of said slit.

MARGUERITE MILLER. 15
